VIBRATILE BOARD FOR ACOUSTIC TREATMENT

Albert B. Hurley, Huntington, N. Y.

Application July 17, 1941, Serial No. 402,793

7 Claims. (Cl. 181—33)

1

This invention relates to the acoustic treatment of ceilings and walls for purposes of sound control.

The primary object of my invention is to generally improve the treatment of walls for noise absorption, or improved acoustics, or sound control in general. Another general object is to provide an improved tile or board for that purpose.

The science of sound control has undergone considerable development in recent years, and a number of companies manufacture tile or board of various kinds for this purpose. Some of these materials are matted wood fibre, porous gypsum, artificial stone using expanded mineral aggregate, mineral fibre or rock wool in pad or blanket form, baked rock wool and clay mixture, asbestos fibre appropriately cemented with or without the admixture of other materials, etc. Some of these products rely solely on the porosity of the material, while others additionally provide holes in the material in an effort to improve the sound absorption.

If the results obtained by the use of these materials is studied, it will be found that the sound absorption efficiency is substantially greater for higher audible frequencies than for the low frequencies. One primary object of my invention is to improve the efficiency for low frequencies. With this object in view the tile or board is provided with peripheral cuts which separate the same into a marginal mounting portion and a vibratile center or diaphragm portion located within the marginal mounting portion. These peripheral cuts operate to weaken the connection between the diaphragm portion and the marginal portion in order to increase the flexibility of the connection, thereby facilitating vibration of the diaphragm portion. This enhances the dampening or absorption efficiency of the board for low frequency sound.

An ancillary object of my invention is to particularly increase the flexibility of the connections, or as I term the same, the "bridges" between the marginal and diaphragm portions. With this object in view, I provide auxiliary cuts at the bridges transverse to the peripheral cuts, thereby lengthening and so increasing the flexibility of the bridges. When dealing with tiles of ordinary square dimension, it is most convenient to form the bridges by means of diagonal cuts at the corners of the tile.

A further object of my invention is to utilize known methods of improving the sound absorption efficiency for high audio frequencies and for

2

this purpose a number of different expedients may be employed, such as the provision of apertures in a thin tile made, for example, of enameled sheet metal or plastic, or the provision of holes (round or elongated slots) part way through or all the way through a relatively thick porous tile made, for example, of wood pulp, matted wood fibre, porous gypsum, or the like. Where the tiles are to be secured to furring strips, as is usually the case, a space is inherently provided in back of the vibratile diaphragm. In some cases, particularly with a thin perforated tile, it may be preferred to place sound absorbing pads or blankets made of a loose fibrous material such as mineral wool, in this space between the furring strips, but such pads are not at all essential with my invention. In rarer cases the tile may be cemented directly on a wall without furring strips, but in that case it should be provided with peripheral ledges, which are either added to the tile or molded integrally with the tile, in order to provide the necessary space in back of the diaphragm.

A further object of the invention is to obtain a more level response for the absorption of low frequencies, and for this purpose a number of tiles may be made, each having a different natural resonance frequency. In one aspect, this object of the invention concerns provision of convenient methods of controlling the natural vibration frequency of the tile. The different frequency tiles may be applied to a wall or ceiling in appropriately staggered arrangement. In some cases, a predominant number of tiles of a particular frequency may be used, depending on the acoustic problem raised in any particular installation.

In accordance with a further feature of my invention, multiple diaphragms may be provided on a single board. Thus a large board may be sub-divided into, say, four diaphragms, each dimensioned as though formed in a board only half as long and half as wide as the actual board. This reduces the amount of labor attendant upon nailing up the boards. In other cases a small diaphragm may be formed at the center of a large diaphragm, thus providing a diaphragm resonant to one low frequency at the center of a larger diaphragm which is resonant to another low frequency.

Acoustic tiles having a diaphragm action are not broadly new, one such tile being made, for example, by Heerwagen Acoustic Decoration Company. However, such diaphragm tiles as have been made heretofore have been delicate

in structure and difficult to apply, and while they may be helpful in eliminating some particular rumbling reverberation or booming sound, are little or not at all helpful for sound absorption of high audio frequencies. They suffer from the serious limitation of being useful only for low frequencies. Thus, while acoustic tiles are already available for high or low frequencies alone, their efficiencies fall off very sharply for low or high frequencies respectively. With my invention, both low and high frequencies may be taken care of.

To the accomplishment of the foregoing and such other objects as will hereinafter appear, my invention consists in the acoustic tile features and their relation one to the other as herein-after are more particularly described in the specification and sought to be defined in the claims. The specification is accompanied by drawings, in which:

Fig. 1 is a perspective view of a thin metal or plastic board showing the peripheral cuts to facilitate vibration;

Fig. 2 is a fragmentary view of one corner of a cast tile or pulp tile with a blind slot or groove therein;

Fig. 3 is a similar view, but showing a board having a through cut and an elongated bridge;

Fig. 4 is a similar view showing a thin metal or plastic tile with a diagonal bridge;

Fig. 5 is a similar view showing a cast or pulp tile with a diagonal bridge weakened by a longitudinal cut;

Fig. 6 is a similar view showing a tile with through cuts and a modified bridge;

Fig. 7 is similar, but with a further modification of the bridge;

Fig. 8 is a section taken in the plane of the line 8—8 of Fig. 7, and illustrates a method of further weakening or improving the elasticity of the bridge;

Fig. 9 is a similar section, but showing a modification in which the bridge of a relatively brittle cast tile is strengthened by means of an embedded metal reinforce;

Fig. 10 shows one corner of the upper side of a board in which the diaphragm portion is fully separated from the marginal portion but connected thereto by means of a spring bridge;

Fig. 11 shows a cast tile having a diagonal bridge strengthened by flexible means cemented thereto;

Fig. 12 is a section taken in the plane of the line 12—12 of Fig. 11;

Fig. 13 is explanatory of how the boards of my invention may be secured to furring strips;

Fig. 14 illustrates how the marginal portions of a board may be thickened if the board is to be cemented to a wall;

Fig. 15 illustrates such boards cemented to a wall;

Fig. 16 shows how the boards may be provided with integrally thickened marginal portions;

Fig. 17 illustrates boards of this character cemented to a wall;

Fig. 18 is explanatory of the fact that the various boards here illustrated, while shown with simple square edges, may be interlocked by appropriate known joints;

Fig. 19 shows how the diaphragm portion of a thick porous board may be provided with blind holes;

Fig. 20 is a similar view showing how the board may be provided with blind intersecting slots;

Fig. 21 shows a modification having through holes and an elongated diagonal bridge;

Fig. 22 is a modification having through slots;

Fig. 23 is a modification using biased or sloping slots;

Fig. 24 shows a modified arrangement of angular slots;

Fig. 25 illustrates a thin metal or plastic tile having through slots and perforations;

Fig. 26 is a similar view showing a thin tile having slots;

Fig. 27 shows how the thin tiles may be mounted on furring strips;

Fig. 28 is a modification in which the space between the furring strips is occupied by blankets or pads of mineral fibre or rock wool or like absorbent material;

Fig. 29 illustrates a modification using crossed furring strips;

Fig. 30 shows a laminated material made up of a thin metal or like hard-surfaced tile secured directly to a porous pulp tile;

Fig. 31 is a similar view in which the porous tile is slotted in registration with the perforations in the metal tile;

Fig. 32 is a section through a modification in which the metal tile is spaced somewhat from the porous tile, said section being taken approximately in the plane of the line 32—32 of Fig. 33;

Fig. 33 is a bottom plan view of the same;

Fig. 34 is a fragmentary section drawn to larger scale and showing a modification;

Figs. 35, 36, and 37 are fragmentary views showing how the resonance frequency of a tile may be varied by changing the length of the bridge or the width of the bridge, or both;

Figs. 38, 39, and 40 are sections taken longitudinally of the bridge (as in Fig. 8) and show how the resonance frequency of the tile may be changed by changing the thickness of the bridge;

Figs. 41, 42, and 43 are sections through a resilient bridge, and show how the resonance frequency of the tile may be changed by varying the length or the thickness of the resilient bridge, or both;

Fig. 44 shows how a smaller diaphragm may be formed in a large diaphragm;

Fig. 45 shows how different frequency tiles may be staggered when using tiles of, say, five different frequencies;

Fig. 46 shows how a tile of one frequency may be multiplied relative to the others, depending on the needs of any particular installation;

Fig. 47 illustrates the use of tiles of only two frequencies, one of these being used more than the other to fill the needs of a particular installation;

Fig. 48 shows how multiple diaphragms may be formed on a single large board to facilitate installation of the boards;

Fig. 49 shows how holes (to aid high frequency absorption) may be provided all over a tile including even the marginal portion thereof;

Fig. 50 shows a partially cut away composite tile in which a thick vibratile diaphragm is concealed by a highly perforate thin metal cover plate; and

Fig. 51 is a fragmentary section drawn to enlarged scale and taken approximately in the plane of the line 51—51 of Fig. 50.

Referring to the drawings, and more particularly to Fig. 1, I there show a board or tile 12 made of thin hard material. It may, for example, be made of metal appropriately painted

or enamelled. It may also be made of a thermoplastic material, such as Bakelite or other similar plastics, from which boards or panels are made by impregnating fabric, paper, or wood veneer. In accordance with my invention the tile is provided with peripheral cuts 14, 16, 18, and 20. These divide the tile into a marginal mounting section or portion 22 and a center or diaphragm section or portion 24. The marginal mounting portion may be secured to furring strips or the like, by means of nails, screws, or other suitable fasteners. Because of the peripheral cuts the diaphragm portion 24 may vibrate readily relative to the marginal portion. This vibration under the impact of low frequency sound waves serves to dampen and absorb the sound waves. The cuts are not continuous, the interruptions therebetween leaving rigid and flexible spaced connections 26 which may be termed "bridges."

Referring now to Fig. 2, I there show one corner of a tile or board which may be made of a suitable porous material. Known commercial materials may be used, such as those made by the Celotex Corporation which makes Acousti-Celotex out of perforated fibre, Muffletone out of cast porous gypsum, Calicel which is an artificial porous stone made out of expanded mineral aggregate, and Absorbex made out of matted wood fibres. Other suitable materials are made by Johns-Manville Corporation, who make Permacoustic out of baked rock wool and clay; Spongeacoustic out of asbestos fibre, natural sponge, and cement; Fibretex which is made out of wood fibre; Transite which is made out of asbestos and cement; and Airacoustic which is made out of rock wool and a suitable binder. A number of other companies make sound absorbing tiles or boards including Armstrong Cork Company, National Gypsum Company, and United States Gypsum Company.

In accordance with the present invention, the tile 30 is peripherally cut or slotted as indicated at 32 and 34. In the present case, the slots do not go all the way through the board and therefore the cuts may be continuous, the connection between the diaphragm portion 36 and the marginal mounting portion 38 being provided by the uncut thickness indicated at 40.

In Fig. 3 I show a board or tile in which the diaphragm portion 42 is adapted for freer vibration relative to the marginal mounting portion 44. This result is obtained by the use of through cuts 46 and 48 which are not connected end to end, thus leaving a bridge 50. In the present case, an additional cut 52 is provided parallel to but spaced from the cut 48, thus elongating the bridge 50 and so increasing its flexibility. This, of course, makes the diaphragm portion 42 more readily vibratile.

In Fig. 4, I show a tile of the thin hard variety, such as metal or plastic, but in this case the bridge 52 between the cuts 54 and 56 is elongated by the use of diagonal cuts 58 at each side of bridge 52. This obviously increases the ease of vibration of the diaphragm portion 60.

Fig. 5 illustrates a thick porous tile having cuts or slots 62 and 64 which pass nearly but not wholly through the thickness of the material. A diagonal bridge is provided at each corner, this being formed by diagonal cuts 66, and the bridge may be further weakened for improved vibration by a diagonal center cut 68 extending longitudinally of the diagonal bridge

and dividing the same in effect into two narrower bridges.

Fig. 6 illustrates a thick porous tile, the diaphragm portion 70 of which is connected to the marginal mounting portion 72 by means of a diagonal bridge 74 formed by diagonal slits 76. These, as well as the main cuts 78, pass all the way through the material. In this case the diagonal cuts 76 extend outwardly from the peripheral cuts 78.

In Fig. 7 the diagonal cuts 80 extend inwardly and outwardly of the peripheral cuts 82, thus providing an elongated bridge 84 which yieldably connects the diaphragm portion 86 to the marginal mounting portion 88.

Fig. 8 illustrates how the diagonal bridge may be further weakened for freer vibration, particularly when dealing with a thick tile or board. In Fig. 8, which is a section taken longitudinally of the bridge 84 in Fig. 7, it will be noted that the bridge portion 84 is cut away at the back, as is indicated at 90. This constitutes another means for controlling the vibration of the diaphragm portion, particularly when dealing with thicker or stiffer materials.

Some materials, such as cast gypsum, may prove to be troublesome because of their brittle or frangible nature. Thus with tiles having a diaphragm portion connected to the marginal portion solely at the corner bridges, difficulty may arise because of breakage of the bridge during shipment or handling. This difficulty may be overcome by reinforcing the bridges, and one method of doing this is illustrated in Fig. 9 in which a sheet metal strip 92 preferably made of resilient material, such as spring metal, is embedded in the tile at the bridge during casting of the tile. If desired, the ends of the spring metal may be bent to form spacers or feet 94 on which the reinforce 92 may rest in the mold during the casting operation. It will be understood that the section of Fig. 9 is taken longitudinally of the bridge, or in the same direction as Fig. 8, and that the metal reinforce 92 is simply an elongated 45 rectangular strip disposed longitudinally of the bridge.

A simpler method of reinforcing the bridge is that illustrated in Figs. 11 and 12 in which the reinforcing strip 96 is simply cemented to the bridge 98 on the upper or inner face of the tile. In the present example the reinforcing strip 96 is a thin strip of wood.

If desired, a thin strip of flexible material, such as spring metal, may be used as the entire bridge. An example of this is shown in Fig. 10 in which the diaphragm portion 100 is completely separated from the marginal portion 102 by means of a continuous peripheral cut 104. They are again connected together, however, by means of 60 spring metal strips 106 secured thereto by suitable means such as screws. The resulting bridges may be located diagonally at the corners of the tile, as shown in Fig. 10, and, of course, are preferably located on the back or inner surface of the tile.

Fig. 13 illustrates one manner in which the sound absorbing tiles or boards may be mounted on a wall or ceiling. Furring strips 108 are preliminarily fastened to the wall at proper spacing, and the tiles are then secured thereto in edge to edge relation by suitable means such as concealed nails. It will be understood that the center to center spacing of the furring strips corresponds to the width of the tiles. It will also be understood that the marginal mounting portions of

the tiles are sufficiently wide to bring the peripheral cuts within or between the furring strips or, in other words, to localize the diaphragm portion to the space between the furring strips, so that the diaphragm portion is freely vibratile.

While in the preceding and succeeding illustrations I show the tiles with simple square edges, it will be understood that any of the known interlocking edges may be employed in order to give the finished wall or ceiling a more ornamental appearance, and in order to conceal the nails and to facilitate fastening the tiles in place. Many such interlocking connections are already known, and a typical one is that illustrated in Fig. 18, in which two adjacent edges of each tile are provided with a male edge 110, while the other two edges have a mating female edge 112. These fit together in a manner clearly shown in the drawings, and leave an ornamental V-shaped scoring 114 exposed to the eye.

In some cases it may be more convenient to secure the sound absorbing tiles directly to a wall as by means of cement, without using any furring strips. For this purpose the marginal mounting portion of the tile is preferably thickened on the back in order to provide at least a little space to accommodate the vibration of the diaphragm portion, and to provide a sufficiently large air space therebehind.

In Fig. 14 an ordinary flat tile is shown thickened at its side edges by the addition of strips of material 116, these being cemented to the two opposite marginal portions of each tile as a part of the manufacture of the tile. The other two edges have been left open, for free air movement. Fig. 15 illustrates the attachment of these tiles to a wall 118.

In Fig. 16 I show a more advanced and preferable arrangement in which the thickened marginal portions 120 are formed integrally with the remainder of the tile by appropriate shape of the mold used to manufacture the tile. These tiles are shown cemented to a wall or ceiling 122 in Fig. 17. In Figs. 15 and 17 the clearance shown has been minimized, and in many cases a larger air space may be wanted, and can, of course, be provided. Also ledges may be provided on all four edges, if it is desired to isolate the action of each tile.

As so far described, the tiles are peripherally cut and are so mounted as to afford vibration of most of the area of the tile for purposes of improving the efficiency of the tile for dampening low frequency sounds. High frequency sounds may be absorbed or deadened by the porous nature of the material from which the tile is made. If desired, however, the efficiency of the tile for absorption of high frequency sounds may be enhanced by the provision of suitable holes (by which term I include also slots) cut part way or all the way through the tile.

Specifically, in Fig. 19 the diaphragm portion 124 is provided with holes 126 which pass part way through the material. The spacing, diameter, and depth of these holes may be selected in accordance with known methods heretofore developed in connection with similar boards already made in a commercial way, but, of course, devoid of the peripheral cuts 128 for facilitating vibration of the center portion acting as a diaphragm to dampen low frequencies.

Fig. 20 is a modification in which the holes for improving the efficiency of the unit for high frequency take the form of elongated slots 130 arranged transversely to another series of elongated

slots 132. These are in addition to peripheral cuts 134 which free the diaphragm portion for vibration.

The holes for high frequency sound absorption may pass entirely through the tile, and this is illustrated by the holes 136 shown in Fig. 21. This figure, incidentally, illustrates the use of diagonal cuts 138 to elongate the bridge 140 between the peripheral cuts 142.

In Fig. 22 the holes for high frequency dissipation take the form of through slots 144. With through slots, it is, of course, not possible to use transversely arranged slots as shown in Fig. 20. In Fig. 22 the peripheral cuts 146 lead to a bridge 148 which extends parallel to one side of the tile, rather than diagonally thereof. The bridge is elongated by means of an extra cut 150.

Fig. 23 illustrates a porous board having peripheral cuts 152 and slots for high frequency sound, these slots being disposed at an angle relative to the plane of the tile. There are slots 154 which slope toward the left, as viewed in Fig. 23, and slots 156 which slope toward the right. These intersect at a common opening 158.

Fig. 24 is similar, except that the oppositely sloping slots 160, 162 are entirely separate from one another.

Fig. 25 shows a thin material such as sheet metal or plastic provided with peripheral cuts 164, diagonal cuts 166 forming an elongated bridge 168, and perforations 170 to improve the efficiency for high frequencies.

In Fig. 26 there are peripheral cuts 172 to divide the tile into a center diaphragm portion 174 and a marginal mounting portion 176. Instead of perforations the tile portion 174 has slots 178. In the case of a thin material, such as that shown in Figs. 25 and 26, the improvement in high frequency dissipation is due to the passage of sound through the perforations into the space in back of the tile where the sound is reflected, dissipated, and absorbed. Thus the tile should be spaced from the wall not only to afford vibration of the diaphragm, but also to improve the dissipation of high frequency sound. This is illustrated in Fig. 27, in which furring strips 180 are preliminarily secured to a wall 182, following which the thin tiles 184 are secured to the furring strips. The tiles 184 may have the features of Fig. 25 or Fig. 26, or any desired combination of these features.

Instead of using an unoccupied air space in back of the tile, this space may be filled by a fibrous material such as mineral fibre or rock wool. These materials are now made in the form of pads or blankets which may be laid between the furring strips, as is indicated at 186 in Fig. 28. In other respects, Fig. 28 corresponds substantially to Fig. 27.

In Fig. 29 I illustrate a modified arrangement in which the pads or blankets or fibrous material may be held in position by additional furring strips. Specifically, a series of parallel furring strips 188 are preliminarily secured to wall 190 in spaced relation. The pads or blankets 192 are laid between the furring strips 188 and are held in position by fastening transverse furring strips 194 to the furring strips 188. The furring strips 188 are properly spaced to receive the previously made up pads or blankets. The furring strips 194 are properly spaced to properly fit the tiles 196. These tiles may have the features of Fig. 25 or Fig. 26, or any desired combination of these features.

In some cases it may be desirable to employ a laminated tile made up of a thin hard surface material and a thick porous material. For example, the sound absorbing property of the thick porous material may be wanted together with a sanitary washable surface as, for example, in hospitals or the like. Such a tile is shown in Fig. 30, it comprising a thin hard material 200 cemented to a thick soft porous material 202. The combined or laminated board is peripherally cut at 204 in order to free the center portion for vibration. The center portion of the thin lamination is perforated as is indicated at 206, thus admitting sound to the porous material where it tends to be absorbed.

Fig. 31 shows a modification in which the thick porous backing material 208 is slotted at 210, these slots being disposed behind and registering with the holes 212. This improves the efficiency with which sound is admitted to the porous backing material.

With the tile shown in Figs. 30 and 31 a space must be provided in back of the diaphragm to afford vibration of the same. This is readily done when the tiles are to be secured to furring strips. If the tiles are to be cemented directly to a wall, then it is necessary to provide thickened edges as was described in connection with Figs. 14 through 17. However, a modified tile may be made in which the thin surface material vibrates while the thick porous material is cemented directly to the wall. Such an arrangement is shown in Figs. 32, 33, and 34. In this case the laminated tile comprises a thin hard surface material which is dished or bent near its periphery to displace it from the porous backing material. Specifically, the complete tile comprises a porous back 214 and a metal front 216, the latter being bent at 218 to space the diaphragm portion from the backing board. The metal or outer material is peripherally cut as is indicated at 220, thus freeing the diaphragm portion for vibration. The parts may be secured together by the use of eyelets 222, these being convenient because nails and screws for securing the laminated tile in position may be passed through the eyelets. However, the present form of tile is ideally suited for cementing to walls because the entire back of the porous tile may be cemented to the wall. Low frequency sound tends to be damped by vibration of the diaphragm, while high frequency sound passes through the perforations and is dissipated in the porous material.

Fig. 34 illustrates a modification in which the backing board 224 is provided with parallel slots 226 to aid in the absorption of high frequency sound in the porous material. These slots may register with the lines of holes 228 through the sheet metal diaphragm, but such registration is not essential because of the space between the sheet metal surface material and the porous material.

An advantage of the laminated forms of the invention shown in Figs. 30 and 31 is that the boards are imperforate in respect to low frequencies, thus obtaining maximum efficiency of vibration as a diaphragm. From the viewpoint of theory and the gathering of performance data, it is a simplification to use an imperforate diaphragm, and from this viewpoint the peripheral cuts which free the diaphragm from the marginal portion should preferably be thin slits rather than wide slots, that is, there should be little appreciable width to the cut if the cut is

a through one. This helps divide the action of the tile as a diaphragm, on the one hand, and as an absorption medium, on the other. With through holes in the diaphragm the theory becomes more complex. Much previously known data on the absorption of high frequencies may be employed while using blind holes or slots.

In making the above observation, I do not mean that it is undesirable or unsatisfactory to use through perforations or through slots to aid in the absorption of high frequencies. I mean merely that the performance of the diaphragm as a diaphragm for the absorption of low frequencies will be affected by an appreciably extensive area of through perforation, and the performance data must be appropriately modified.

While speaking of performance characteristics of the tiles, it may be well to point out that the air space in back of the tile affects the natural resonance frequency of the diaphragm. Thus, if the performance data of a particular tile is obtained while mounting the tile on furring strips which are two inches thick, the tile should afterward be used on similar furring strips which will similarly space the tile two inches from the wall. A change to a spacing of only one inch from the wall will change the performance of the tile. In general, a substantial space is better than a small space where structural considerations make the use of a substantial space feasible. Also a free movement of air in back of the tiles is thought desirable by many.

In actual practice a number of different tiles are preferably provided having different natural resonance frequencies. This is desirable in order to level off the absorption of low frequencies over the entire low frequency range. For example, there might be five different frequency tiles all in the low frequency range. As a random example they might respond to or peak at 64, 128, 256, 384, and 512 cycles, respectively.

This different frequency response may be obtained by making the bridges wider or narrower or by making them longer or shorter, or by making them thicker or thinner. Thus, referring to

Figs. 35-37, I there show three tiles which are similar, except that in Fig. 35 the bridge is long; in Fig. 36 it is of medium length; while in Fig. 37, it is short. In Fig. 35 the bridge is narrow; in Fig. 36 it is of medium width; and in Fig. 37 it is wide. Either or both of these changes in dimension may be employed with a view to changing the flexibility of the bridge, and thereby changing the natural resonance frequency of the tile.

In Figs. 38, 39, and 40 I show sections through the bridge (generally similar to the section shown in Fig. 8) but in Fig. 38 the bridge is of minimum thickness; in Fig. 39 it is of medium thickness; and in Fig. 40 it is of increased thickness. The bridge of Fig. 38 is more flexible, and that of Fig. 40 is less flexible, than that shown in Fig. 39.

In Figs. 41, 42, and 43 I show how the same adjustment may be made with a tile having a separate resilient bridge member. In Fig. 41, the bridge 230 and the undercut 232 therebeneath are short; in Fig. 42 the bridge 234 is of medium length and the same applies to the undercut 236 therebeneath, while in Fig. 43 the bridge 238 is of maximum length and the same applies to the undercut 240 therebeneath. Thus the bridge of Fig. 41 will be less yieldable and that of Fig. 43 will be more yieldable than that shown in Fig. 42. In this form of the invention the diaphragm 242 is cut free of the marginal portion 244 by

means of the peripheral cut 246. The undercut beneath the bridge provides clearance to accommodate flexing of the spring strip. The end portions of the bridge beyond the undercut are secured to the material of the tile in any suitable manner, as by cementing the same in position.

Instead of changing the length of the resilient bridge it may be changed in width (not shown but analogous to Figs. 35-37) or it may be changed in thickness. This is illustrated in the drawings in which the bridge of Fig. 41 is thicker and the bridge of Fig. 43 is thinner than that shown in Fig. 42. It will be understood that any one or more of these methods of changing the natural resonance frequency of the tile may be employed. It will also be understood that while three different dimensions have been illustrated, a greater number may be employed, and in practice it may prove desirable to have, say, five different frequency tiles.

For a uniform response these may be arranged in staggered relation, one such relation being shown in Fig. 45, in which the tiles marked 1, 2, 3, 4, and 5 correspond to five different frequencies. It will be understood that each of these tiles is provided with peripheral cuts and bridges for the diaphragm action, and is preferably provided with holes for high frequency absorption. It will be noted that the first horizontal row is arranged in sequence from 1 through 5; that the same applies to the second horizontal row, except that it begins with tile No. 3; while the third horizontal row begins with tile No. 5; the fourth horizontal row begins with tile No. 2; the fifth horizontal row begins with tile No. 4; and the sixth horizontal row repeats the first horizontal row, that is, it begins with tile No. 1.

In most cases the acoustics of a room or hall may actually be measured before the sound absorbing treatment is applied thereto. In such case it may be found that increased corrective use of a certain frequency tile is needed relative to the other tiles. Thus in Fig. 46 it is assumed that the number of No. 1 tiles is to be doubled. Each horizontal row is shown arranged with a No. 1 tile between the No. 3 and No. 4 tiles, thus doubling the number of No. 1 tiles, but distributing the same uniformly. The succeeding rows begin with different tiles as, for example, the order shown in which the sequence vertically is the same as that horizontally. Other arrangements may, of course, be employed.

In measuring the acoustics of a room, it may be found that only one or two different frequency tiles are needed, and it may be found that one of these is needed more than the other. Such a situation is illustrated in Fig. 47, in which the tile is being treated with only the No. 2 and No. 3 tiles, and with twice as many No. 3 tiles being used as No. 2 tiles. These may be appropriately staggered in any desired relation.

In practicing the present invention, it is possible to so cut a large board or tile as to form more than one diaphragm therein. Such an arrangement is shown in Fig. 48 in which the wall has furring strips 250 and is covered with boards 252 which are, say, four feet square. This board is so cut as to form four diaphragms 254 which correspond in size to what would normally be used with a two foot tile. This facilitates and speeds up the operation of covering a ceiling or walls, because only a smaller number of boards must be secured in position. Furring strips may be used on two foot centers, thus supporting the

large board at the middle as well as at the edges. It is possible to vary the bridges of the four diaphragms, thus providing four different frequency diaphragms on a single board. However, for the sake of simplicity, and in order to permit of flexibility in installing any desired frequency diaphragms in any desired proportion for each problem, one may make the four diaphragms in Fig. 48 alike, the large board then acting as a nest of four diaphragms all having a common resonance frequency.

In Fig. 44 I show a different arrangement having more than one diaphragm formed on a single board. In this case there is a rather small diaphragm 260 located at the center of a large diaphragm 262. The small diaphragm may be designed to have a natural resonance frequency in the high part of the low frequency range, while the large diaphragm 262 may be designed to have a natural resonance in the low part of the low frequency range. All these diaphragms may be provided with holes 264 to aid high frequency absorption. In the specific case here shown the holes are elongated blind slots, arranged in crossed formation. It will be understood, however, that round holes may be used, and that the holes may be located in the marginal as well as the diaphragm portions of the complete tile.

Fig. 49 may be referred to as showing the use of holes for high frequency absorption applied all over a tile including the marginal portion as well as the diaphragm portion. This may be done because the operation in respect to high frequencies does not depend upon the diaphragm vibration. Overall use of holes provides a more uniform surface appearance for the wall, which may be of advantage in some instances.

Figs. 50 and 51 show an arrangement in which a thin (for example, metal) surface material 261 is combined with a thick absorbent material 263, the metal being dished at 265 and secured to the tile 263, as by means of eyelets 266. The complete tile is mounted on furring strips 268, so as to be spaced from the wall in order to afford vibration of the thick absorbent material 263. This is peripherally cut as indicated at 270, and may be provided with diagonal cuts and bridges, all as previously described. The metal covering plate 261, however, is not provided with peripheral cuts and need not vibrate. It is made very highly perforate, as is indicated by the closely spaced holes 272. It is made so highly perforate as to afford adequate free transmission of low frequencies, which then cause vibration of the diaphragm 263, there being no appreciable vibration of the surface material or covering plate 261. This, however, may be used in order to present an attractive enamel finish where such a finish is desired. There is also the benefit of having two air spaces, because some high frequency sound absorption takes place in the air space between the laminations 261 and 263.

It will be understood that one of the factors in determining the natural resonance frequency of the tile is the mass of the vibrating diaphragm. This depends on its size and thickness as well as on the density of the material. Thus in Fig. 44 the diaphragm 262 has a much larger mass than the diaphragm 260, which, in turn, results in a difference in resonance frequency.

There is a conflict of opinion as to whether the air space in back of the vibrating diaphragm should or should not be sealed. Some authorities say that there should preferably be a communication from one tile to the next. This is ob-

tained by using furring strips without any cross pieces which might interfere with free flow of air in the longitudinal spaces between the furring strips. Similarly, when pieces are cemented to the back of a tile as in Fig. 14, they are desirably cemented along only two edges, rather than all four edges. The same applies when using molded edges as in Fig. 16, but in this case it is also possible to simply interrupt the edges to form several short well-spaced projections along all four edges. However, if it is desired to isolate the effect of each tile, then cross-pieces must be used, or in the case of Figs. 14 and 16, the raised edges should extend entirely around the periphery of the tile. One treatment may be better for sound absorption, say, at the back of an auditorium, and the other may be better for sound reflection, say, at the stage, but this difference is not critical to my invention, which is applicable to either the open or the sealed treatment.

It is believed that the method of making and using my invention, as well as the advantages thereof, will be apparent from the foregoing detailed description. The improved board or tile acts as a diaphragm and vibrates under the impact of low frequency sound waves. It dampens the waves, the energy being dissipated in the bridges. The high frequency waves pass into or through the diaphragm and are there deadened or dissipated. The improved tile corrects one of the important defects of previously known tiles, namely, the fact that they are efficient over only one end or the other of the audio range. With my improved tile the best known efficiency for high frequencies may be retained without loss, and efficient operation in the low frequency range is superimposed on that. Relatively free vibration of tiles made of known materials is obtained in comparatively simple fashion by the use of peripheral cuts which free the center or diaphragm portion from the marginal or mounting portion. The resulting spaced bridges may be made more flexible by elongating them, or thinning them, or both, and if necessary the bridges may be reinforced to strengthen the same. The tiles may be mounted on furring strips or may be provided with thickened edges and mounted directly on a wall. Holes may be provided to improve the absorption of sound and these may be round or elongated and may pass part way through or entirely through the tile. The space in back of the tile may be left vacant or may be filled with a fibrous material such as mineral or rock wool. The tile may be laminated of several materials, and if desired one of these may be vibrated relative to the other. In all cases the edges of the tiles may be appropriately shaped to form interlocking joints.

Tiles having different natural frequencies may be provided, and different selections and proportions of these tiles may be used in accordance with the requirements of any particular installation. Multiple diaphragms may be formed in a single tile or board. Holes for high frequency response may be formed in the diaphragm or the marginal portion or both.

It will therefore be apparent that while I have shown and described my invention in a number of preferred forms, many changes and modifications may be made in the structures disclosed without departing from the spirit of the invention, as sought to be defined in the following claims. In the claims the term "peripheral cut" is intended to apply to a cut which frees the diaphragm portion for vibration, whether these cuts

extend part way or all the way through the material. The term "bridge" is intended to mean any connection which holds the diaphragm portion to the marginal mounting portion, whether or not elongated. The expression "hole" in connection with high frequency absorption is intended to include either a through hole or a blind hole, and either a round hole or elongated hole such as a slot.

10 I claim:

1. An acoustic tile comprising a central enclosed vibratile diaphragm section and a marginal diaphragm-enclosing mounting section, the diaphragm section being inwardly spaced from the mounting section by a peripheral opening therebetween, the diaphragm section being rigidly connected to the mounting section by bridge elements bridging said peripheral opening, the diaphragm section thereby forming a vibratile member freely set into vibration at said rigid bridge elements on the mounting section under the impact of sound waves, the free vibration of said vibratile member serving to absorb the said sound waves.

2. An acoustic tile comprising a central enclosed vibratile diaphragm section and a marginal diaphragm-enclosing mounting section, the diaphragm section being spaced inwardly from the mounting section by peripheral diaphragm-defining cuts, the diaphragm section being rigidly connected to the mounting section by bridge elements bridging said peripheral cuts, the diaphragm section thereby forming a vibratile member freely set into vibration at said rigid bridge elements on the mounting section under the impact of sound waves, the free vibration of said vibratile member serving to absorb said sound waves.

3. An acoustic tile comprising a central vibratile diaphragm section and a marginal diaphragm-enclosing mounting section, both sections being made of the same material, the diaphragm section being spaced inwardly from the mounting section by peripheral diaphragm-defining cuts produced in said material, the diaphragm section being rigidly connected to the mounting section by bridge elements bridging said peripheral cuts, the diaphragm section thereby forming a vibratile member freely set into vibration at said rigid bridge elements on the mounting section under the impact of sound waves, the free vibration of said vibratile member serving to absorb said sound waves.

4. An acoustic tile comprising a central enclosed vibratile diaphragm section and a marginal diaphragm-enclosing mounting section, the diaphragm section being spaced inwardly from the mounting section by peripheral diaphragm-defining cuts, the diaphragm section being rigidly connected to the mounting section by bridge elements bridging said peripheral cuts, the diaphragm section thereby forming a vibratile member freely set into vibration at said rigid bridge elements on the mounting section under the impact of sound waves, the free vibration of said vibratile member serving to absorb said sound waves, the said bridge elements being provided with cuts transverse to the peripheral cuts to lengthen and thereby increase the flexibility of the bridges.

5. An acoustic tile comprising a central enclosed vibratile diaphragm section and a marginal diaphragm-enclosing mounting section, the diaphragm section being spaced inwardly from the mounting section by peripheral diaphragm-defining cuts, the diaphragm section being rigidly con-

15

ected to the mounting section by bridge elements bridging said peripheral cuts, the diaphragm section thereby forming a vibratile member freely set into vibration at said rigid bridge elements on the mounting section under the impact of sound waves of relatively low frequency, the free vibration of said vibratile member serving to absorb said sound waves, the said diaphragm being provided with holes in order to increase the absorption of high frequency sound.

6. An acoustic tile comprising a central enclosed vibratile diaphragm section and a marginal diaphragm-enclosing mounting section, both sections being made of the same material, the diaphragm section being spaced inwardly from the mounting section by peripheral diaphragm-defining cuts produced in said material, the diaphragm section being rigidly connected to the mounting section by bridge elements bridging said periph-

16

eral cuts, the diaphragm section thereby forming a vibratile member freely set into vibration at said rigid bridge elements on the mounting section under the impact of sound waves, the free vibration of said vibratile member serving to absorb said sound waves, the said bridge elements having predetermined dimensions to predetermine the vibration period of said diaphragm.

7. An acoustic tile structure comprising in combination a plurality of acoustic tiles as defined in claim 1, in which the diaphragm sections are connected to the mounting sections solely by means of the bridge elements, and in which the bridge elements of different tiles are of different dimensions in order to vary the natural resonance frequency of some of the diaphragms relative to other diaphragms.

ALBERT B. HURLEY.
